HOOP ROLLER

Salvatore D. Timpani, 119 Furlong Road,
Brighton, N.Y. 14623

Filed Apr. 12, 1971, Ser. No. 133,467

Term of patent 14 years

Int. Cl. D21—01

U.S. Cl. D34—5 HP

FIG. 1 is a fragmentary side elevational view of a hoop roller embodying my new design;

FIG. 2 is a fragmentary front elevational view thereof; and

FIG. 3 is a sectional view taken along the line 3—3 in FIG. 2 looking in the direction of the arrows.

The characteristic feature of my design resides in the particular handle configuration in combination with the manipulating shaft that bends to offset the U-shaped end laterally from the center line of the shaft and bends at the lower end so that the handle and shaft are angularly inclined to the plane of the U-shaped end.

I claim:

The ornamental design for a hoop roller, substantially as shown and described.
